United States Patent Office

Des. 184,129
Patented Dec. 23, 1958

184,129

TOY BANK

James Brannon Hull, Zanesville, Ohio

Application August 2, 1957, Serial No. 47,197

Term of patent 7 years

(Cl. D34—11)

FIG. 1

FIG. 2

Fig. 1 is a front perspective view of a toy bank, showing my new design; and

Fig. 2 is a rear perspective view thereof.

What I claim is:

The ornamental design for a toy bank, as shown.
